(57) **CLAIM**

The ornamental design for a clamp for a photovoltaic module mounting assembly as shown and described.

DESCRIPTION

FIG. 1 a rear perspective view of a clamp provided in a position of use relative to a photovoltaic module mounting assembly and a photovoltaic module;

FIG. 2 is a rear perspective view thereof;

FIG. 3 is a front perspective view thereof;

FIG. 4 is a front elevation view thereof;

FIG. 5 is a rear elevation view thereof;

FIG. 6 is a right elevation view thereof;

FIG. 7 is a left elevation view thereof;

FIG. 8 is a top plan view thereof; and,

FIG. 9 is a bottom plan view thereof.

The evenly-spaced broken lines are included for the purpose of illustrating environment and portions of the clamp for a photovoltaic module mounting assembly that form no part of the claimed design. The dot-dash broken lines are included for the purpose of illustrating the bounds of the claim and form no part of the claimed design.
